GIMBAL MECHANISMS

James Langley Russell, Luton, England, assignor to The English Electric Company Limited, London, England, a British Company

Application December 28, 1953, Serial No. 400,729

Claims priority, application Great Britain January 9, 1953

3 Claims. (Cl. 74—95)

This invention relates to a gimbal mechanism; i. e. a mechanism comprising a gimbal member upon which a device is pivotally mounted, a gimbal member itself being mounted on a frame pivotally about an axis perpendicular to a plane containing the pivotal axis of the device in the gimbal member.

According to a feature of the present invention, a mechanism comprises a gimbal member having two co-extensive part-circular opposed concentric surfaces, means to support the gimbal member comprising two rollers both bearing upon one of the surfaces and at least one other roller bearing upon that part of the other surface corresponding to the minor arc between said two rollers, and means to move the gimbal member circumferentially between the rollers.

According to a further feature of the invention, said means to move the gimbal member comprises a pair of flexible rope-like members fastened one near each end of an outwardly facing surface of the gimbal member and passing around this surface over each of a pair of adjacently disposed pulleys to a means for applying and controlling tension in the rope-like members. Said rope-like members may be lengths of cord, wire-rope, chain or tape, etc.

According to another feature of the invention, the means for applying and controlling tension comprises a pair of fluid pressure-controlled piston and cylinder units in which the rope-like members are each fastened to a piston attachment.

According to a preferred feature of the invention the means for applying and controlling tension comprises a pair of fluid pressure-controlled piston and cylinder units in which the rope-like members each pass over a pulley mounted on a piston attachment and have the ends which are not fastened to the surface of the gimbal member fastened to a fixed point in the mechanism.

According to a still further feature of the invention said pair of adjacently disposed pulleys is formed by grooves in the two rollers which bear upon the surface of the gimbal member.

A gimbal mechanism which embodies the invention in preferred form is diagrammatically illustrated in plan view in the accompanying drawing.

A semi-circular gimbal ring 10 supports, through pivotal bearings 11 and 12, the axis of which lies in the plane of the figure, a reflector dish 13 for a radar aerial.

The gimbal member 10 is in turn supported from a frame (not shown) by passing between two rollers 14 and 15 which are carried by the frame and bear upon the outside surface of gimbal member 10, and a further roller 16 which bears on the inside surface and is also carried by the frame.

2

A flexible wire 17 is secured to gimbal member 10 at 18 and is wrapped around the outside surface of gimbal member 10 to pass between this member and roller 14. It then passes around a further roller 19 and has its other end secured to the frame at a point 20.

A similar flexible wire 21 is secured to the other end of gimbal member 10 at point 22 and passes between the gimbal member and roller 15, around roller 23 to an anchorage on the frame at point 24.

10 Roller 19 is secured to a piston 25 by a piston rod 26. Piston 25 works in a hydraulic cylinder 27 to force roller 19 away and apply tension to wire 17. Roller 23 is similarly forced by a corresponding piston 28 and hydraulic cylinder 29 to apply tension to wire 21.

15 By application of pressure fluid through the port 31 to cylinder 27 at higher pressure than fluid applied through the port 32 to cylinder 29, the tension in wire 17 may be increased above that in wire 21. Piston 25 will then move outwards expelling fluid through the port

20 33 while piston 28 moves inwards and fluid is admitted through the port 34 and gimbal member 10 will be turned between rollers 14, 15 and 16 in the direction which appears anti-clockwise in the drawing. The ports 33 and 34 may be connected together.

25 Rotation of reflector 13 about the axis of its bearings 11 and 12 is independently effected by a motor diagrammatically indicated at 30.

It will be seen that the mechanism shown in the drawing can be constructed to occupy a space of small over-all width, which in some applications is a great advantage.

30 What I claim as my invention and desire to secure by Letters Patent is:

1. A mechanism comprising a gimbal member having two co-extensive part-circular opposed concentric surfaces, means to support the gimbal member comprising two rollers both bearing upon one of the surfaces and at least one other roller bearing upon that part of the other surface corresponding to the minor arc between said two rollers, and means to move the gimbal member circumferentially between the rollers.

35 2. A mechanism according to claim 1, wherein said means to move the gimbal member comprises a pair of flexible rope-like members fastened one near each end of an outwardly facing surface of the gimbal member and passing around this surface over each of a pair of adjacently disposed pulleys to a means for applying and controlling tension in the rope-like members.

40 3. A mechanism according to claim 2, wherein said pair of adjacently disposed pulleys is formed by grooves in the two rollers which bear upon the surface of the gimbal member.
